UNITED STATES PATENT OFFICE.

EDITH WRIGHT, OF GERMANTOWN, PENNSYLVANIA.

FASTENING CLASP.

Application filed March 28, 1924. Serial No. 702,628.

This invention relates to a fastening clasp and refers particularly to such a device designed for use in connection with clasp envelopes or the like.

5 The particular object of this invention is to provide an envelope clasp which is easy and inexpensive to manufacture, of extreme simplicity; and one which is positive of its clasping action when in use.

10 Other objects and advantages of this invention will be apparent from the following description taken in conjunction with the accompanying drawings, in which:

Figure 1 is a plan view of an envelope with the flap thereof in open position showing the clasp in position on said envelope.

Figure 2 is a plan view of an envelope in closed position with the clasp shown in locked position.

20 Figure 3 is a perspective view of the clasp. Figure 4 is a sectional view of the clasp in open position.

Figure 5 is a cross-sectional view on the line 5-5 of Figure 2.

25 Figure 6 is a view of a modified form of the clasp.

Referring now, more particularly, to the drawings, the clasp, as will be seen in Figures 3 and 4, comprises a single piece of flexible material such as a strip of thin metal, having a lower section 2, the extreme lower end of the latter being provided with prongs 3 for securing the clasp to an envelope. The lower section 2 is further provided with oppositely arranged prongs 4 which prongs are positioned just below the middle of the entire strip. If desired, the strip may be scored as shown at 5' at a line substantially midway between the ends of the strip, for a purpose to be hereafter described.

40 The strip, more particularly portion 2 thereof, is provided with an opening 5, which is shown as rectangular but which obviously might be of any shape desired, said opening being arranged substantially midway of the lower portion 2 of the strip.

The end of the upper portion 1 of the strip is bent upwardly as shown at 6 and preferably has its edges tapered as shown at 7.

45 A tongue 8 is provided which is preferably triangular in shape and which is struck upwardly from the material of the upper portion 1 of the strip, said tongue being positioned substantially at right angles to the material of the strip and immediately

below the upwardly bent end or guard 6.

In Figure 6 I have illustrated a modification of the clasp in which the material of portion 2 of the strip is struck downwardly to form a guideway 9 which will guide the tongue 8 into locking position as will be hereafter described.

In use the clasp is attached to an envelope as shown in Figure 1, with the prongs 3 and 4 supporting the clasp by engaging the material in an obvious manner. The closing flap of the envelope is provided with an opening 10 and it will be obvious from an inspection of Figure 2 that the upper portion 1 of the strip will pass through the opening 10 and is folded over upon portion 2 of the strip (see Figure 5), the tongue 8 being pressed through the material of the closing flap of the envelope and passing into the opening 5 whereupon a slight pressure on the end of portion 1 of the strip will serve to bend a tongue 8 to the position shown in Figure 5. The free end of portion 1 of the strip will assume the position 80 shown in Figures 2 and 5, the end 6 serving as a guard as will be obvious, and the tapered edges 7 will facilitate the easy removal of the clasp from its locked position when desired.

85 While I have found the structure shown in Figures 3, 4 and 5 to be fully satisfactory in use, I have devised the modification shown in Figure 6 wherein the material of the lower portion 2 will serve as a means for guiding the tongue 8 into the position shown in Figure 5. This type of clasp is particularly adapted for satisfactory use where the material of the envelope is of such texture that the tongue 8 will not readily fold to the 95 position illustrated in Figure 5.

From the above it is believed that the structure and operation of this invention will be fully apparent to those skilled in the art but I desire it understood that while the drawings show the preferred embodiment of the invention, various changes in the form and proportions of the device may be made such as fall within the scope of the appended claims without departing from the spirit of 100 the invention.

Having thus described my invention what I claim and desire to secure by Letters Patent of the United States is:

1. A clasp comprising a piece of foldable 110 metal having on the lower portion thereof a plurality of sets of prongs for attaching

the clasp to an envelope or the like, said lower portion being provided with an opening between said sets of prongs, and a tongue on the upper portion of said metal, 5 and so positioned as to enter said opening when the metal is in folded position whereby to secure the clasp to the envelope or the like.

2. A clasp comprising a piece of metal 10 adapted to be folded upon itself forming upper and lower sections, a plurality of sets of prongs on the lower section, said lower section being provided with an opening between said sets of prongs, the end of said 15 upper section being bent to form a guard, and a tongue struck from the material of said upper section and so positioned as to enter the before mentioned opening.

3. A clasp of the kind described comprising 20 a piece of foldable material having a weakened section intermediate the ends thereof defining a line of fold for said material, oppositely arranged prongs at the lower end of said material, oppositely arranged 25 prongs on said material adjacent the weakened section, said oppositely arranged prongs being so formed and arranged as to attach the clasp to an envelope or the like, said material being provided with an opening 30 between said sets of prongs, and a tongue struck from the upper portion of the material and so positioned as to enter the before mentioned opening when said

material is in folded position and retain the folded portion in interlocking relation 35 with the remaining portion.

4. A clasp of the kind described comprising a piece of foldable material having a plurality of sets of prongs on the lower portion thereof, one of said sets defining the line of fold for the material, said material having between said sets of prongs a portion struck therefrom forming a guideway, a tongue formed on the upper portion of said material and so positioned as to engage said guideway when the material is in folded position and to retain the two sections thereof in interlocked relation. 45

5. A clasp comprising a piece of foldable material having on the lower portion thereof a plurality of oppositely disposed sets of prongs for attaching the clasp to an envelope or the like and an opening between said sets of prongs, an upper portion having a prong struck from the material thereof at a point removed from the ends of said upper portion and a bent end forming a guard, said upper portion being so arranged as to be folded over upon said lower section with the prong of said upper section 55 within the opening in said lower section whereby to secure the clasp to an envelope or the like. 60

In testimony whereof I affix my signature.

EDITH WRIGHT.
